UNITED STATES PATENT OFFICE.

BERNARD T. STEBER, OF UTICA, NEW YORK.

NEEDLE-DEPRESSING MECHANISM FOR KNITTING-MACHINES.

SPECIFICATION forming part of Letters Patent No. 654,813, dated July 31, 1900.

Application filed April 18, 1900. Serial No. 13,367. (No model.)

To all whom it may concern:

Be it known that I, BERNARD T. STEBER, a citizen of the United States, residing at Utica, in the county of Oneida and State of New York, have invented certain new and useful Improvements in Needle-Depressing Mechanism for Knitting-Machines; and I do hereby declare the following to be a full, clear, and exact description of the invention, such as will enable others skilled in the art to which it appertains to make and use the same.

My invention relates to improvements in knitting-machines, and particularly to mechanism for use in depressing needles which have been thrown out of action.

It consists, in a knitting-machine provided with the usual knitting-needles and a cam-cylinder, of an inclined arm adjustably mounted upon the cylinder and adapted to extend at one end into the path of the heels of the needles, a weight upon the said arm for holding it in or out of action, and a cam mounted upon the machine for throwing the arm into action ready to depress the needles.

It also consists in certain other novel constructions, combinations, and arrangements of parts, as will be hereinafter fully described, and specifically set forth in the claims.

In the accompanying drawings, Figure 1 represents a top plan view of a portion of a knitting-machine provided with depressing levers or arms. Fig. 2 represents an enlarged detail view of a portion of the cam-cylinder of a knitting-machine, showing a slide carrying a needle-depressing arm. Fig. 3 represents a perspective view of a bracket for holding the needle-depressing arm and its slide. Fig. 4 represents a perspective view of the slide. Fig. 5 represents a perspective view of a needle-depressing arm or lever. Fig. 6 represents a detail view in elevation of the cam mounted upon the knitting-machine for throwing the needle-depressing arms into position for engaging the heels of the needles. Fig. 7 represents a bracket having a dovetailed groove formed therein for holding the arm-carrying slide. Fig. 8 represents a detail perspective view of a grooved bracket adapted to hold the arm in its elevated position when not in use. Fig. 9 is a detail view showing a slide-supporting bracket having a

different-shaped dovetailed groove formed therein.

My improved needle-depressing mechanism is adapted for use particularly in connection with circular-knitting machines which employ needle-cylinders, as 1, having grooves for receiving vertically-moving knitting-needles, as 2 2. The heels of the said needles are guided also by a guide-frame, as 3, the said 60 heels projecting through slots formed therein and extending sufficiently beyond the same to be engaged by cams carried upon a cam-cylinder 4. The cam-cylinder 4 is adapted to be rotated either continuously in one direction or the other or back and forth for producing various kinds of fabric and for shaping the said fabrics in various ways. In knitting certain kinds of fabrics—as, for instance, in finishing the feet, heels, or toes of stockings or socks—it is necessary to have some of the needles out of action and to return the same into action one at a time upon each side of the machine as the knitting operation progresses. I have devised a means for automatically returning the needles into action first upon one side of the machine and then upon the other, the same comprising needle-depressing arms or levers 5 5, located at one or more points upon the periphery of the cam-cylinder 4. In order to accommodate these arms, I preferably construct outwardly-extending walls at suitable points upon the cam-cylinder, as at 6 6, thereby forming recesses to accommodate the said levers or arms and 80 the adjustable slides 7 7, which carry the same. These walls form a break in the contour of the cam-cylinder at its upper edge and inclose the arms or levers 5 5 sufficiently to protect them. This structure also obviates the necessity of weakening the cam-cylinders by cutting slots through them to accommodate the depressing-arms. Because of the peculiar manner in which these arms engage the heels of the needles it is desirable to mount 90 the arm so as to move in an inclined plane. The slides 7, which carry the said arms, are therefore adjustably secured to brackets 8 8, secured in the enlargements of the cylinder 6 6, the said brackets having inclined projections formed with grooves, as 9 9, in their under surfaces. Each of the slides 7 is provided

with a rib, as 10, adapted to engage the groove 9 in its particular bracket, and a set-screw, as 12, extending through a slot 13 in the bracket, engages the slide 7, holding it so that 5 its rib 10 will always engage the groove 9. The said screw 12 is not screwed in sufficiently far to clamp the slide 7 to the bracket, but is made sufficiently loose to permit the said slide to be moved back and forth. The 10 slide 7 is provided with a shank or stem, as 14, which projects through the wall of the enlargement 6 and is provided with a milled head, as 15, upon its outer end for moving the slide back and forth. The milled head may 15 be provided with a projection 16, if desired, which is adapted to engage a notch 17, formed in a boss 18 upon the enlarged portion 6.

A coiled spring, as 19, is interposed between the slide 7 and the inner surface of the enlargement 6, so that the slide is normally pressed inwardly by the action of the said spring. When the projection 16 is brought into engagement with the notch 17, the slide can be forced to its innermost position, so as to 25 bring the needle-depressing arm which it carries into proper position for engaging the heels of the needles. By grasping the milled head 15 and pulling it outwardly so that the projection 16 is disengaged from the recess 17 the said 30 milled head may be turned and the projection 16 be caused to engage the edge of the boss 18, so as to hold the slide 7 in its outer position and draw the depressing-arm out of action.

It will be apparent that the groove 9 in the 35 bracket 8 might be made of a different shape. Thus, as seen in Fig. 7 of the drawings, the bracket may be constructed with a dovetailed groove 20, adapted to receive a correspondingly-shaped rib upon the slide 7. By this 40 construction the set-screw 12 may be dispensed with, as the dovetailed groove will hold the slide from falling away from the bracket. So, also, as seen in Fig. 9 of the drawings, the 45 groove may be made of a slightly-different shape, as at 21, without departing from the spirit of the invention.

Pivottally secured to the adjustable slide 7 in each enlargement 6 is a needle-depressing arm or lever 5, which is fulcrumed at a point about 50 midway of its length, as at 22, and is provided at its free end with a notched needle-engaging portion, as at 23. The other end of the arm 5 carries an upwardly-curved arm, as 24, which carries a weight, as 25. The weight is 55 so located with respect to the pivotal part of the arm that when the lever is thrown into engagement with the needles the weight will hold it in that position and when the needle-depressing arm is thrown out of engagement 60 the weight will hold it in that position, the weight being thus moved back and forth upon each side of a line passing through the pivotal point of the arm 5.

As seen in Fig. 1 of the drawings, when the 65 slide 7 is in its innermost position and the arm 5 is brought to a horizontal position its inner needle-engaging end 23 will be in the path of

the heels of the needles 2. The arm when in this position is, however, so high upon the cylinder that it only engages the heels of the 70 needles which have been lifted out of action. As the cylinder is revolved and the heel of a needle is approached by an arm, it will engage the notched end 23 thereof. The continued rotation of the cylinder will cause the 75 heel of the needle to press against the arm, which will tend to move the said arm upon its pivotal point. As the arm, however, is arranged upon an incline, as it moves upon its pivoted point it will draw the heel of the 80 needle downwardly and will continue to draw it downwardly until the arm, because of its pivotal movement, is carried away from the needle, by which time the heel of the needle will be sufficiently low to engage the under 85 surface of the slide 7. The slide 7, it will be noted, extends inwardly when the arm 5 is in working position to engage the heels of the 90 needles and depress them sufficiently to place them in a line with the working cams of the machine.

In order to automatically throw the levers 5 into position, I preferably mount upon a top plate 26 a cam 27, which, as seen in Fig. 6 of the drawings, is provided with inclined faces 95 upon each edge. After one of the arms 5 has been brought into engagement with the heel of a needle and been swung downwardly its weight will hold it in that position until the cam-cylinder has made approximately 100 one revolution, when the arm 24 will come into engagement with the cam 27 and be thrown outwardly, its weight holding it in said position. By throwing the arm 24 outwardly the lever 5 is again brought into a 105 horizontal position ready to engage the heel of the next needle. When the cylinder is rotated in the other direction, the arm 24 of the other depressing-needle 5 is brought into contact with the cam 27 and is thrown into 110 active position in turn. Thus the needles of a machine which have been drawn out of action for a time may be returned into action one at a time upon each side of the machine. This is particularly useful in the knitting of 115 the heels, feet, and toes of stockings, as set forth by me in an application filed heretofore upon a circular-knitting machine and bearing Serial No. 4,376.

It is desirable when the depressing-arms are 120 withdrawn from action to hold them positively against movement, and for this purpose I contemplate mounting a grooved bracket, as 28, in the enlargements 6, the said brackets being arranged so that their bifurcated 125 ends 29 will engage the ends 23 of the said depressing-arms when the slides 7 are drawn outwardly. Thus the arms 5 will be held against movement while they are out of action.

It will be apparent from the foregoing description that my improved depressing-arms may be used in connection with knitting-machines of various kinds which employ cam-cylinders and needles having heels and that

the said arms may be located at one or more suitable points upon the peripheries of the said cylinders, so that they may be made to actuate the needles at various times. It will 5 also be apparent that these arms can be thrown into and out of action at any time when it is desired to depress one or more needles which have been brought out of action. It will be seen also that the adjusting 10 of the said arms back and forth can be quickly accomplished by the manipulation of the milled heads 15.

Having thus described my invention, what I claim as new, and desire to secure by Letters 15 Patent, is—

1. A needle-depressing mechanism for knitting-machines, comprising an arm pivoted upon an incline and adapted to move back and forth to either side of the pivot-point, a 20 weight connected with one end of the arm for automatically holding the arm in either position according as it may be thrown, and a needle-engaging portion formed at the other end, the action of the weight being to hold the 25 arm in or out of operative position.

2. A needle-depressing device for knitting-machines, comprising an arm pivoted to a switch-slide, a switch-slide carrying the said arm and adapted to be moved back and forth 30 for carrying the arm into and out of active position, and means for holding the said arm automatically in position for engaging the needles or out of said position, as desired.

3. A needle-depressing mechanism for knitting-machines, comprising an arm having a notched end for engaging the heels of the needles at one end, an arm projecting from the other end thereof having a weight secured thereto, the weight being so arranged with respect to the pivotal point of the depressing-arm that when it is thrown into or out of action the weight will be thrown to one or the other side of the said pivotal point for holding the arm in its changed position.

4. A depressing mechanism for knitting-machines, comprising an adjustable slide, an enlargement upon the cam-cylinder, of the knitting-machine for accommodating said slide, an arm, a bracket mounted in said enlargement and means for adjustably securing the slide to the bracket, the construction being such that by moving the slide back and forth the pivotal arm carried by the slide may be brought into or out of engagement with the heels of the knitting-needles.

5. A depressing mechanism for knitting-needles, comprising an inclined slide, means for adjustably mounting the same upon a knitting-machine, a pivoted arm carried by 60 the said slide for drawing the needles into engagement with the same, the said arm being so pivoted as to move in an inclined plane, a weight connected with the said arm for holding it in or out of active position, and means 65 for moving the slide so that it will be brought in position to receive the needles from the pivoted arm.

6. In a knitting-machine, the combination with a cam-cylinder having enlargements formed thereon, of brackets secured therein, 70 slides secured to the said brackets, means for loosely holding the slides against the brackets, means for moving the slides back and forth, a needle-depressing arm pivoted to the said slides and adapted to extend into the path of 75 needles which are raised out of action when the slide is pushed inwardly, and a cam upon the machine for bringing the arms into active position after having been depressed by one 80 of the needles.

7. In a knitting-machine, the combination with a cam-cylinder having enlargements formed thereon, of brackets mounted therein and provided with guiding-grooves, slides adapted to move on the said brackets and 85 having ribs engaging the said guiding-grooves for holding them in proper alinement, means for loosely holding the slides against the brackets comprising set-screws passing through elongated slots formed in the brackets, and stems secured to the said slides, and thumb-nuts secured to the slides for drawing them back and forth, substantially as described.

8. In a knitting-machine, the combination 95 with a cam-cylinder having a portion of its walls extended to form a recess, a bracket mounted in the recess, said bracket having a slide-carrying groove formed therein, a slide provided with a rib for engaging the said 100 groove, a stem upon the slide extending through the wall of the enlargement, a milled head secured to the outer end of the stem and provided with a detent or projection adapted to engage a notch formed in a boss on the said 105 enlargement, and a spring interposed between the slide and the wall of the enlargement for normally pressing the slide inwardly, and a pivoted needle-depressing arm carried by the said slide, the structure being such 110 that by the manipulation of the milled head the slide may be adjusted and held in its inner or outer position, substantially as described.

9. In a knitting-machine, the combination with a cam-cylinder having its walls extended 115 to form recesses, a pivoted slide mounted in each of said recesses, means for adjusting the same in and out, a needle-depressing arm pivoted to the said slide and having a needle-engaging notch at one end, and a weighted arm 120 at the other end, a bracket having a bifurcated end portion secured in the said enlargement and adapted to engage the end of the said lever, whereby it will be held stationary when out of active position, and means for 125 operating the said lever when in active position, so as to bring it into proper relation with the heels of the needles for depressing the same, substantially as described.

10. In a knitting-machine, the combination 130 of a cam-cylinder having enlargements formed therein, lever-carrying slides mounted upon an incline in each of the said enlargements, pivoted needle-depressing arms car-

ried by the said slides, curved weighted arms secured to the ends of the said depressing-arms adapted to hold the arms in or out of position, a plate mounted upon the knitting-machine and provided with a cam having inclined faces, the structure being such that when the cylinder is rotated in one direction it will engage one of the curved weighted arms and throw its depressing-lever into operative position, and when the cam-cylinder is rotated in the opposite direction it will bring the other weighted lever against the said cam and throw its depressing-lever into operative position, substantially as described.

11. In a knitting-machine, the combination with a cam-cylinder, of a needle-depressing mechanism carried thereby, outwardly-extending walls on the said cylinder forming a

recess to receive the needle-depressing mechanism, a suitable support for carrying the needle-depressing mechanism secured to the inner surface of one of said walls, the said depressing mechanism comprising a lever-carrying fulcrum mounted upon the said support and extending obliquely to the line of movement of the needles, and a needle-engaging arm carried by the said fulcrum, the construction being such that the needle-depressing mechanism is sufficiently inclosed to be well protected, substantially as described.

In testimony whereof I hereunto affix my signature in presence of two witnesses.
